(57) **CLAIM**

We claim the ornamental design for a weigh platter or cover for a data reader, as shown and described.

DESCRIPTION

FIG. 1 is a front, top, right isometric view of a front portion of a weigh platter or cover for a data reader showing the new design;

FIG. 2 is a rear right isometric view thereof;

FIG. 3 is a right side elevation view thereof, the left side elevation view being a mirror image duplicate;

FIG. 4 is a rear side elevation view thereof.

FIG. 5 is a top plan view thereof; and,

FIG. 6 is a front side elevation view thereof.

The broken line elements are not claimed. The appearance of the underside of the invention is not claimed and is therefore not disclosed in the drawing views.
